UNITED STATES PATENT OFFICE.

JACOB LOWENTHAL, OF CHICAGO, ILLINOIS.

ADJUSTABLE STANDARD FOR MIRROR-FRAMES, &c.

SPECIFICATION forming part of Letters Patent No. 707,707, dated August 26, 1902.

Application filed February 8, 1902. Serial No. 93,146. (No model)

To all whom it may concern:

Be it known that I, JACOB LOWENTHAL, a citizen of the United States, residing at Chicago, in the county of Cook and State of Illinois, have invented certain new and useful Improvements in Adjustable Standards for Mirror-Frames and other Articles, of which the following, when taken in connection with the drawings accompanying and forming a part hereof, is a full and complete description, sufficient to enable those skilled in the art to which it pertains to understand, make, and use the same.

The object of this invention is to obtain an adjustable standard for mirror-frames and other articles by means of which the frame may be placed in any desired position, as by swinging the bracket of the standard on its base and also by moving the frame at the end 20 of the bracket into any desired plane.

The manner in which I obtain the object sought by me is by constructing a bracket pivoted to its base in the ordinary way and attaching the mirror-frame or other article to 25 the outer end of such bracket by a universal joint of peculiar construction, as herein set forth.

I have illustrated the device embodying this invention in the drawings referred to as 30 accompanying this specification, and wherein—

Figure 1 is a side elevation of a bracket, the base of such bracket, a frame, and a universal joint by means of which the frame is 35 attached to the bracket. Fig. 2 is a side elevation of the bracket illustrated in Fig. 1, such bracket being turned in its base, so that such base is shown in front elevation, a rear elevation of the frame illustrated in Fig. 1, and 40 a combined side and rear elevation of the universal joint of the device. Fig. 3 is a side elevation of the ends of the bracket to which the universal joint is attached and of a short section of one of the shafts of the universal 45 joint. Fig. 4 is a horizontal sectional view of the end of the bracket which is illustrated in Fig. 3 on line 4 4 of such Fig. 3. Fig. 5 is a perspective view of a U-shaped sheet-metal piece (preferably made of spring metal) 50 forming an element in the universal joint by means forming the connection between the bracket and the frame supported thereby.

Fig. 6 is a top plan view of the base of the universal joint, such base being attached to the backing of the frame and preferably made 55 of spring metal; and Fig. 7 is a side elevation of the base illustrated in Fig. 6.

A reference-letter applied to designate a certain part is used to indicate such part throughout the several figures of the drawings 60 wherever the same appears.

A is a bracket pivoted at one end thereof, as by pins or bolts *a a*, to base B. Base B may be attached to a wall or other thing, as by screws *b b*.

65 C is a frame, and C' is the backing of such frame.

D is a base, preferably made of spring sheet metal.

E is a shaft having flattened ends. Base 70 D and shaft E are attached to the backing C' of frame C, as by the bolts *e e*, having nuts *e' e'* thereon.

d d are friction springs coming in contact with the curved portion of U-shaped piece F. 75 The springs *d d* are preferably integral with base D and are formed or punched up from such base in the manner shown in Figs. 6 and 7. The U-shaped piece F extends around the body of the shaft E and is attached to the 80 free end of bracket A by rivet or bolt *f*. When the part F is constructed of spring sheet metal, the bolt or rivet *f* is drawn or set sufficiently tight to obtain sufficient friction between such U-shaped piece F and the end 85 of the bracket A, so that the frame C when adjusted to any plane by the turning of the U-shaped piece F on its pivot will be sufficiently stable to remain in its adjusted position. When the U-shaped piece F is not 90 made of spring metal, the springs G G are placed into the recesses H H on the bracket A, between such bracket and the U-shaped piece F.

To provide for wear of bolt, pin, or rivet *f* 95 and also of the body of the shaft E and at the same time to obtain sufficient friction between the base D, shaft E, and the U-shaped piece F, the end *a'* of the bracket A (see Fig. 3) is made concentric with the hole *f'* in such 100 bracket, (through which hole the bolt or rivet *f* extends,) with the radius of such part *a'* sufficiently long, so that the shaft E is in contact with the periphery thereof.

To limit the movement of the shaft E and frame C around the bolt or rivet f, the end of the bracket A adjacent to the circular part a' is cut away on substantially the lines a² a².

5 The operation of this apparatus is: When bracket A has been adjusted on its base B to any desired position, the frame C is turned into any desired plane by the movement of the U-shaped part F on its pivot f and the 10 turning or rocking of shaft E in the U-shaped part F. The friction between the several parts D E F is sufficient to hold the mirror in its adjusted position.

Having thus described my invention, what 15 I claim as new, and desire to secure by Letters Patent, is—

1. The combination of a frame, a backing, such backing secured in the frame, a bracket, such bracket provided with a hole adjacent 20 to one end thereof and provided with a circular end concentric with the hole, a U-shaped piece, a pivot, such U-shaped piece provided with a hole near the bend therein and attached to the bracket by extending the pivot 25 through the holes in the U-shaped piece and in the bracket, a shaft, such shaft flattened at its ends and arranged relative to the U-shaped piece and bracket to be interposed between the bend of the U-shaped piece and the circular 30 end of the bracket, a base, such base provided with friction-springs stamped out of and forced up therefrom, and such base

interposed between the shaft and the backing of the frame, and means to attach the base and the flattened ends of the shaft to 35 the backing: substantially as described.

2. The combination of a frame, a backing, such backing secured in the frame, a bracket, such bracket provided with a hole adjacent to one end thereof and with recesses in its 40 sides near the hole, and provided with a circular end concentric with the hole, a U-shaped piece, a pivot, such U-shaped piece provided with a hole near the bend therein and attached to the bracket by extending the pivot 45 through the holes in the U-shaped piece and in the bracket, springs interposed between the bracket and the U-shaped piece and held in the recesses in the bracket by the U-shaped piece, a shaft, such shaft flattened at its ends 50 and arranged relative to the U-shaped piece and the bracket to be interposed between the bend of the U-shaped piece and the circular end of the bracket, a base, such base provided with friction-springs stamped out of 55 and forced up therefrom, and such base interposed between the shaft and the backing, and means to attach the base and the flattened ends of the shaft to the backing; substantially as described.

JACOB LOWENTHAL.

In presence of—

CHARLES TURNER BROWN,
CORA A. ADAMS.
